UNITED STATES PATENT OFFICE

BRUNO R. SCHABARUM, OF TOLEDO, OHIO, ASSIGNOR TO THE NATIONAL SUPPLY COMPANY, OF TOLEDO, OHIO, A CORPORATION OF OHIO

GAS-LIFT PUMP

Application filed May 27, 1927. Serial No. 194,590.

My invention relates to gas lift pumps of the type wherein at one stage compressed gas (a term herein used broadly enough to include air) acts as a piston to force the liquid to be pumped downwardly in one column in a well and upwardly in another column; and at the succeeding stage the compressed gas enters and aerates the rising liquid column and expanding therein causes the column to rise and flow to a desired place at the surface of the ground.

It is the principal object of this invention to provide a gas lift pump wherein the valve or valves therein are controlled by the velocity of the fluid being pumped. Other objects pertain to details which will be better understood after they have been explained.

Referring to the accompanying drawing, Fig. 1 is a side elevation of a string of well tubing containing my invention, parts being broken away, and a central vertical section of the well casing; Fig. 2, a central enlarged longitudinal section of one of my valves and the adjacent portions of the well tubing; Fig. 25 3, a section on the line III—III on Fig. 2; and Fig. 4, a section on the line IV—IV on Fig. 2.

On the drawing, 1 designates a well casing having at its top a casing head structure 30 provided with the lateral inlet 2 and the cap 3 which screws down on the casing. The upper length 5 of the well tubing extends from the top of the well down through the cap and into the casing, the cap having the 35 stuffing box 6 surrounding the length 5. 7 is a gland on the stuffing box for compressing the packing 8 in the stuffing box fluid-tight around the said length 5.

To the lower end of the length 5 of the 40 tubing or to the lower end of tandem lengths of tubing coupled together I screw the special coupling 9 which constitutes the fixed member of my valve. This member comprises the tubular body 10 having near its 45 lower end the internal shoulder 11, on which the tubular sliding or reciprocable valve member 12 rests when at its lower limit. The upper end of the body 10 has the end ring 13 screwed thereinto and is provided with 50 the annular skirt or lip 14 projecting into

the body, this lip forming a stop for the valve member when at its upper limit. A helical spring 15 is seated on the top of the valve member 12 and against the lower side of the end ring 13 between the lip 14 and the inner surface of the body 10. The spring tends to keep the valve member 12 on the shoulder 11. The body 10 has lateral ports 16 with which the ports 17 in the valve member 12 register when the latter is on the shoulder 11. When the member 12 is at its upper limit its ports 17 are wholly above the ports 16 preventing any flow of fluid through said ports. The internal diameter of the valve member is preferably that of the tubing lengths attached to its ends. The passage through the member 12 is restricted in any suitable manner as by an internal web, flange or fin 18 which may, if desired, be extended, as shown, entirely across the member 12 and be provided with one or more openings 19 of suitable size.

The lower end of the coupling 9 may have attached thereto one or more lengths 20 of tubing, to the lower end of which may be 75 screwed another special coupling 9^a provided with all the features that the coupling 9 has. One or more special couplings carrying my valve features may be provided below the coupling 9^a, depending on the height of the 80 head of liquid to be pumped. In some cases one of my valves may be needed. In other cases the tubing string will carry two or more valves.

Assuming that the liquid to be pumped is 85 oil and that the oil level under rock pressure stands at a level above the top valve, compressed gas is admitted through the inlet 2 into the casing 1 above the oil level in the casing and tubing. The gas in the annulus between the casing and the tubing forces the oil down in the annulus and out through the ports 16 and 17, and up the tubing. The predetermined restriction by the web 18 is not 90 large enough to permit the flow of the oil at this stage to lift the valve member 12 and cut off the flow of the oil into the tubing. However, when the level of the oil in the annulus reaches the open ports 16 and 17, gas 95 enters the oil in the casing and aerates it, the 100

globules of oil expanding and causing the aerated mixture to flow out of the tubing at the top of the well. This aeration or levigation of the oil causes a drop of pressure in the 5 tubing above the ports 16 and 17, which will cause an increased velocity of the mixed gas and oil. The restriction by the web 18 is made to be such that this increased velocity of fluid flow will move the valve member 10 upwardly, or in other words, will close the valve.

The gas pressure continuing, the gas level in the annulus is forced on down, causing the oil in the annulus to flow through the ports 15 in the second valve and up the tubing and longitudinally through the upper valve. When the oil level reaches the ports in the second valve, it will close for the same reasons that the first valve closed when the gas 20 escaped through its ports.

Should the oil passing up through the first valve become de-aerated sufficiently, this valve will open, owing to the decreased velocity of fluid flow up through the valve 25 member 12 and against the web 18. Upon the opening of the first valve compressed gas will enter the ascending column of oil in the tubing and aerate it still further, whereby its velocity will be increased, causing 30 the valve to close. The reopening of a previously closed valve helps aerate the un-aerated part of the oil column which has not been aerated by gas passing through the ports in the valve below. The reopening of 35 valves below which the oil level has passed will cease as soon as the column passing them attains the required velocity.

In using the word sleeve in describing the member 12 in the claims, I do not restrict myself to an internal sleeve with an internal web, as the sleeve may be external with the web projecting into the said annulus. In the latter case, the gas would be applied to the liquid in the tubing, the oil being forced up 45 the annulus and out through the passage 2 or otherwise.

It will be noted that the ports 17 are much larger than the ports 16 and that the parts 21 between consecutive parts 12 are very narrow, 50 so that the member 12 may take different axial positions without materially limiting the flow of fluid through the ports.

The spring 15 should be carefully selected so as to prevent the valve member 12 opening either prematurely or tardily.

I claim—

1. In a gas lift pumping string, a well tubing, a hollow member therein, constituting a fixed member and having lateral inlet ports, 60 a hollow movable valve member telescopic with the fixed valve member and having ports registering with the first named ports when the movable member is in one position and out of registry therewith when the movable member is in a second position, a spring 65

tending to move the movable member toward its first position when in its second position, and means carried by the movable member and in the path of fluid flowing through said ports and said tubing for moving the movable member to said second position. 70

2. In a gas lift pump, a well casing, a well tubing, a fixed hollow valve member interposed therein and having lateral inlet ports, a hollow movable valve member telescopic 75 with the fixed member and having ports registering with the inlet ports when the movable member is in its lower position and out of registry therewith when the movable member is in its upper position, means for admitting fluid pressure into the casing above the inlet ports, and means carried by the movable member and in the path of fluid flowing up past the movable member from the said inlet ports and from the tubing 80 below these ports, for moving the movable member to its upper closed position when the velocity of the fluid passing up through the valve reaches a predetermined value. 85

3. In a gas lift pump, a well casing, a well tubing, a fixed hollow valve member interposed therein and having lateral inlet ports, a hollow movable valve member telescopic with the fixed member and having ports registering with the inlet ports when the movable member is in its lower position and out of registry therewith when the movable member is in its upper position, means for admitting fluid pressure into the casing above the inlet ports, and means carried by the movable member and in the path of fluid flowing up past the movable member from the said inlet ports and from the tubing 90 below these ports, for moving the movable member to its upper closed position when the velocity of the fluid passing up through the valve reaches a predetermined value, the said movable member being freely rotatable 95 axially and the parts in one member being sufficiently larger than in the other member so that the rotation of the movable member 100 may not cause appreciable decrease of flow through the ports when in registry. 105

4. In a gas lift pump for liquids, two vertical tubes, one within the other, the inner tube having lateral ports connecting the interiors of the tubes, a valve telescopic with the inner tube and having ports registering with the said inlet ports when the valve is at its lower position and out of registry with the said inlet ports when the valve is at its upper position, means for admitting a compressed gas into the outer tube above the inlet ports for depressing the liquid in the outer tube, forcing it through the said ports and 115 up through the inner tube until the gas enters the said liquid in the inner tube, means carried by the valve above the ports for restricting the flow of the gas-charged liquid upwardly past the valve, the restricting means 120 125 130

being such as to cause the valve to rise and close the said ports when the velocity of the gas charged liquid flowing up through the valve reaches a predetermined velocity.

5. Apparatus of the character described comprising means constituting a conduit and having a fluid admission port, and tubular means associated with the conduit, being responsive to a predetermined mass and velocity of a fluid stream through said means to cause said means to seal-off the port and prevent the passage therethrough of fluid.

6. Apparatus of the character described comprising a pair of fluid conduits, one having a port affording communication between the interiors of the conduits, and means constituting a valve, being subject in its operation to the momentum of fluid flowing in one of the conduits thereby moving toward a sealing-off relationship to the port according to said momentum.

7. Apparatus of the character described comprising a pair of conduits, there being a port in one affording communication between the interiors of the conduits, and a gravitational valve situated in one of the conduits and being co-active with the port in controlling the passage of fluid therethrough, said valve having a formation defining part of the conduit passageway in which it is located, said formation being such that the momentum of fluid passing therethrough will have a lifting effect upon said valve toward said port tending to close the port.

35. 8. Apparatus of the character described comprising a pair of conduits of which one serves as the flow line, a port in one of the conduits affording communication between the interiors of the conduits, and a valve of hollow construction defining part of the passageway of the flow line and being of such formation that the momentum of the fluid flow in said line tends to move the valve toward a sealing-off position over the port.

45. In testimony whereof I hereunto affix my signature.

BRUNO R. SCHABARUM.
